L. CORY.
GAME APPARATUS.
APPLICATION FILED DEC. 26, 1912.

Patented July 7, 1914

UNITED STATES PATENT OFFICE.

LORETTO CORY, OF SHELBYVILLE, INDIANA.

GAME APPARATUS.

Specification of Letters Patent.

Patented July 7, 1914.

1,102,724.

Application filed December 26, 1912. Serial No. 738,622.

To all whom it may concern:

Be it known that I, LORETTO CORY, a citizen of the United States of America, residing at Shelbyville, in the county of Shelby and State of Indiana, have invented certain new and useful Improvements in Game Apparatus, of which the following is a specification.

The present invention relates to games and has for its purpose to provide a game which will offer amusement and at the same time afford instruction to the players while being played.

The invention has for its further purpose to provide a game, the apparatus of which and the manner of playing will considerably depart from all games of this character that have been heretofore known; and it is the further purpose of the invention to offer a game which, while being easily comprehended, will call forth the higher qualities of skill and intelligence on the part of the players.

With these and other objects in view the invention consists in the arrangement and combination of parts hereinafter claimed, and, while the invention is not restricted to the exact details shown and described, still, for the purpose of disclosure, reference is had to the accompanying drawings, in which like reference characters designate the same parts in the several views, and in which,

Figure 1 illustrates the apparatus as in position for playing. Fig. 2 is a detailed perspective view of one of the arches or wickets employed, and Fig. 3 illustrates the preferred form of central stake.

Referring to the several parts of the apparatus, 1 designates the stake which is provided with a lead casting 1^a at its lower end, and said stake is adapted to be provided with a plurality of color bands 2 to correspond with similar colors marked on the handles of the different mallets and balls employed. There are used in the game as many mallets and balls as there are color bands on the stake 1, thus each player is known by the color of the mallet and ball which he uses. Arranged around the course are wickets or arches 5 having each a pair of side portions that are preferably provided with a lead casting or supporting base piece 5^a around the lower ends of their legs. Said wickets or arches are constructed of wire or any other appropriate material and all of the arches are disposed radially of the

center stake 1 and at uniform distance therefrom. It will be obvious, however, that other arrangement of the wickets may be made. There are 28 arches, one for each letter in the alphabet, one for the hyphen sign, and one for the accent mark. These letters and symbols are secured to the arches or wickets in any appropriate manner.

In the form shown in Fig. 2 the wires which are used in making the wickets are bent to provide loops 5^c through which extend rods 5^d whereon is supported a plate 5^e bearing the name of the wicket having the ends bent to embrace rods as at 5^f.

In arranging for the playing of the game, the apparatus is laid out in a circle in substantially the following manner: Place the arch with the "hyphen" mark on it, in an upright position at the head of the court. Place arch with accent mark on it in an upright position, at the foot of the court, which will be directly opposite the hyphen arch. Place the stake exactly in the middle, and on a direct line between arch 80 "hyphen" and "accent" arch. This center is called home. Place arch G at the right-hand side of the court, the same distance from the stake, that arches "hyphen" and "accent" are, and midway between those 85 arches. Place arch T at the left-hand side of court, the same distance from the stake as the other arches are, and exactly opposite to arch G, and midway between "hyphen" arch, and "accent" arch. Place arches A, 90 B, C, D, E, and F the same distance from the stake, and equal distances apart between "hyphen" arch and arch G. These will form the first quarter of a circle. Place arches H, I, J, K, L, and M the same distance from the stake and equal distance apart between arch G and "accent" arch. 95 These complete the half circle. Place arches N, O, P, Q, R, and S the same distance from the stake, and equal distance 100 apart between "accent" arch and arch T. These complete three-quarters of a circle. Place arches U, V, W, X, Y, and Z the same distance from the stake, and equal distance apart between arch T and "hyphen" 105 arch. These complete the circle. Arch "hyphen" is at the head of the court, arch "accent" is at the foot of the court. Arches A to M inclusive are on the right side of the court. Arches N to Z inclusive are on the 110 left side of the court.

The procedure in playing the game and

the rules governing the same are as follows: A captain is chosen who selects the word to be spelled. The captain then takes the ball and mallet whose color entitles him to play 5 first. The other players choose their balls and mallets, and succeed each other in playing in accordance with colors marked upon the home stake. Each player at starting must place his ball within one half of a 10 mallet's length from the home stake, but in any direction from the stake he may wish to place it. The balls must always be driven through the arches on the right-hand side of the court, from the head of the court 15 toward the foot; and through the arches on the left-hand side of the court, from the foot toward the head. Arches from A to M are on the right side of the court and arches N to Z are on the left side of the 20 court. Each player at starting is entitled to two strokes on the first round. The first stroke drives his ball into position for his first arch. The second stroke, he endeavors to drive his ball through the arch. The 25 balls must pass through the arches, in the regular order of the letters in the word being spelled. If a ball be driven only partially through an arch from the wrong side, it is not in a position to be driven through the 30 arch, but must be sent clear of the arch before it is in a position to be driven through correctly. After a ball has been driven through the first arch, if it should strike another ball, the player may croquet the ball 35 out of his way; or place his ball against the ball struck, and take two turns with his own ball, leaving the other ball in its original position. A ball makes an arch when it is driven through by a blow from the mallet 40 or passes through from roquet or croquet. If a player can drive his ball through two arches at one stroke, he is entitled to two strokes. Each player continues to play so long as he drives his ball through the next 45 arch in order or roquets or croquets a ball. Failing to accomplish either of these, he relinquishes his turn to the next player. A player may croquet each of the balls in one turn, but he can not croquet one ball twice 50 without going through an arch. When a

ball has been driven through all the arches in the word being spelled, it may finish by striking the home stake, or it may become a monitor. A monitor continues to play all over the court, giving aid to his partner and 55 trying to prevent his antagonists from making their arches. A monitor may roquet or croquet all the balls, one after another, each turn; but he can not play twice on the same ball in one turn. The game is finished 60 when the balls of the players on one side have been driven through all the arches in the word being spelled, and have struck the home stake.

It is obvious that those skilled in the art 65 may vary the details of construction and arrangement of parts without departing from the spirit of my invention, and therefore I do not wish to be limited to such features except as may be required by the 70 claim. For instance the plate or block may be provided with numerals, words or other symbols or characters as will be obvious.

Having thus described my invention, what 75 I claim as new and desire to protect by Letters Patent is;—

In a game apparatus, the combination of a center starting and finishing stake; a plurality of arches radially disposed and arranged in a circle about the center stake and 80 equally distant therefrom, each of said arches constructed of wire bent to provide parallel members, and a cross member, and said cross member being formed with a pair 85 of circular loops; plates adapted to be marked with alphabetical letters; a pair of rods secured to said plates and fitting in said loops and holding the plates in upright positions; a metal base piece fixed to the lower end of each parallel member for supporting the arch upright on a flat surface; and a ball adapted to be driven through the lettered arches in its travel away from and 90 returning to said stake.

In testimony whereof I affix my signature in presence of two witnesses.

LORETTA CORY.
